UNITED STATES PATENT OFFICE.

LEONARD HARRIS, OF LONDON, ENGLAND.

ANTIVIBRATION PNEUMATIC CUSHION.

SPECIFICATION forming part of Letters Patent No. 783,833, dated February 28, 1905.

Application filed October 25, 1904. Serial No. 229,907.

To all whom it may concern:

Be it known that I, LEONARD HARRIS, a subject of the King of Great Britain, residing at London, England, have invented certain new and useful Improvements in Antivibration Pneumatic Cushions, of which the following is a specification.

It has been heretofore proposed to provide an air-containing flexible or elastic chamber for interposition between two parts or structures from one of which latter it is desired to insulate vibration—as, for instance, between the wheels of a vehicle and the body.

Now the object of the present invention is to provide an improved construction and combination of parts, as hereinafter described and claimed, comprising an antivibration cushion of somewhat globular or like formation provided with an inner air-containing elastic sack, an outer inclosing practically non-extensible but flexible casing and fitted with a valve-controlled inflation-tube, so that the inner chamber can be inflated to such a pressure as to be in accord with the weight to be supported, while at the same time so forming the outer casing that such inflation serves to more firmly hold and secure the cushion within the jaws of oppositely-placed holders secured, respectively, to or forming part of the two structures between which the antivibration cushion is to be placed. To this end the main body of the outer casing to contain the inner elastic air-tight sack is made of practically globular form, having upon opposite sides a circular opening, and around the annular edges of each of these openings is formed or fitted an externally-projecting flange, rib, or other device by which the casing engages two cup-shaped metallic holders which complete the closure of the chamber. The chamber, in conjunction with the cup-shaped holders, then consists of the main globular chamber communicating upon opposite sides with extension-chambers formed by the aforesaid flanged edges around the openings of the chamber, in conjunction with the cup-shaped holders. By the inflation of the inner elastic air-tight sack within this compound outer casing the two structures can be insulated from one another with any desired amount of rigidity, according to the air-

pressure, while the said air-pressure within the chamber firmly holds the outer casing in position without the same being damaged or becoming accidentally detached.

The invention will be fully understood by the following description, having reference to the accompanying drawings, whereon—

Figure 1 shows in elevation an example of construction of my improved antivibration pneumatic cushion complete; and Fig. 2 is a vertical transverse section of the same, Fig. 3 being a diagram showing by way of example one application of the appliance.

Referring to Figs. 1 and 2, the outer casing 1 is shown of mainly spherical form, being made with an opening at its upper and lower parts, the edges of the casing at these openings being formed with annular externally-projecting ribs 2 3, and the said casing is composed of some suitable flexible but practically non-extensible material, a convenient construction being to make the casing of fabric built up upon a mold, then impregnated with india-rubber and vulcanized, or the casing 1, with its ribs 2 3, may be made of india-rubber, with an interior lining of non-extensible fabric, while the ribs 2 3 are suitably strengthened by canvas or provided with annular metallic wires laid in the said annular ribs during manufacture. I thus have a globular non-extensible and flexible outer case open at opposite sides and having at the edges of its openings exterior ribs, the surfaces of the said ribs toward the globular part being of such formation as to be capable of being gripped by the inturned edges or gripping-jaws of cup-shaped holders. 4 5 represent a pair of such cup-shaped gripping-holders with their in-turned flanges or annular jaws 6 7, and within these holders the annular ribs 2 3 of the flexible outer casing 1 can be readily inserted. The edges of the said annular ribs 2 3 are thinned away or tapered, so as to lie flush against the interior of the cup-shaped holders. Placed within the outer casing 1 before it is applied to the gripping-holder 4 is an inner elastic air-tight sack 8, composed of india-rubber and carrying an air-inflation valve 9 of any suitable character, the said valve 9 being passed through a hole drilled in the grip-

ping-holder. Such holders 4 5 are formed with suitable means by which they may be fixed to any structure as required, and in the example shown the said holders are formed 5 with flanges 10 11, by which they are bolted to the parts to which they are to be attached, and it is preferable, as in the construction shown, to arrange that the inflation - valve shall pass through the body of the cup-shaped 10 holder 4 at a convenient angle on one side of the flanges 10 11. With such a construction air may be forced through the valve into the elastic inner sack 8 until it reaches any required pressure at which it is desired to hold 15 apart the two structures to which the cup-shaped holders are attached, and the greater the interior air-pressure the more firmly will the ribs of the outer casing be held within the holders which complete the chamber containing 20 the said elastic inner chamber, while the flexibility of the casing 1 and the elasticity of the air contained in that chamber very effectually absorbs vibration.

The appliance is particularly designed for 25 application between the wheel-axles 12 and bodies 13 of the road-vehicles, particularly such vehicles as are motor-driven, and at Fig. 3 a single example of application is shown, where my improved device, as hereinbefore 30 described, is shown applied to reinforce light springs 14, applied between the wheel-axles and the framework of the vehicle. Such an illustration is, however, only to be taken as illustrating one mode of applying the device, 35 as variations of application are obviously very numerous.

What I claim as my invention, and desire to secure by Letters Patent, is—

1. An antivibration pneumatic cushion; consisting in the combination with a flexible and practically non-extensible casing having oppositely - located circular openings; of two rigid cup-shaped holders, means for fixing the said holders one to each of the two parts of 40 the structure to be insulated from one another with the concavities of the holders located to face each other, an annular seating formed at each edge of the cup-shaped holders, means for connecting the annular edges of the flexible 45 casing to the said seatings of the holders, an elastic air-tight sack in the interior of the compound chamber composed of the outer casing and cup-shaped holders, and an air-inflation valve extending through one of the 50 holders to the said sack for inflating the latter to elastically distance the two parts of the structure, substantially as set forth.

2. In an antivibration pneumatic cushion for elastically distancing two structures; the combination with a flexible and practically non-extensible casing of substantially globular form, having oppositely-located circular openings, and an annular outwardly-projecting rib

on the casing extending around the edge of each opening; of two cup-shaped metallic 65 holders, means for fixing the said holders one to each of the two structures with the concavities of the holders located to face each other, an annular seating formed at each edge of the cup-shaped holders to receive the annular ribs upon the flexible casing, an elastic air-tight sack in the interior of the compound chamber composed of the outer casing and cup-shaped holders, and an air-tight valve extending through one of the holders to the interior of the said sack for inflating the latter, substantially as set forth.

3. In an antivibration pneumatic cushion; the combination with two cup-shaped metallic holders, means for fixing the said holders one to each of the two parts of the structure to be elastically distanced and with the concavities of the holders located to face each other, and inturned annular jaws formed on the facing edges of the cup-shaped holders; of a flexible 85 and practically non-extensible casing of substantially globular form having oppositely-located circular openings in its wall, outwardly-extending annular ribs formed on the casing near the edge of each opening to take into 90 the inturned annular jaws of the cup-shaped holders to form a compound chamber composed of the outer casing and cup-shaped holders, an elastic air-tight sack in the interior of the said chamber, and an air-inflation valve 95 extending through one of the holders to the interior of the said sack for inflating the latter, substantially as set forth.

4. In antivibration pneumatic cushions for interposition between the wheel-axles and bodies of vehicles; the combination with two cup-shaped metallic holders, lugs extending from the convex surfaces of the holders for attaching the said holders one to each of the two parts of the structure to be elastically 100 distanced, the said holders having their concavities opposed to each other and an inturned annular edge to each cup-shaped part to form retaining - jaws; of a practically globular-shaped non-extensible casing of textile fabric 105 and india-rubber, having two oppositely-located circular openings through its wall, an outwardly-projecting annular rib formed on the casing near the edge of each opening to take into the inturned annular edges of the 110 cup-shaped holders, an elastic air-tight india-rubber sack in the interior of the chambers composed by the casing and cup-shaped holders, and an air-inflation valve passing through one of the cup-shaped holders on one side of 115 the holder-lugs aforesaid for inflating the air-tight interior sack, substantially as set forth.

LEONARD HARRIS.
